CLAIM

The ornamental design for a spout, as shown.

DESCRIPTION

FIG. 1 is a front perspective view of a first embodiment, without cover, showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view of a second embodiment, with a cover, of a decorative spout showing my new design;

FIG. 8 is a left side elevational view thereof;

FIG. 9 is a right side elevational view thereof;

FIG. 10 is a top plan view thereof; and,

FIG. 11 is a bottom plan view thereof.

The broken line showing a neck of a bottle in FIGS. 1, 4 and 9 is for illustrative purposes only and forms no part of the claimed design.
